[57] **ABSTRACT**

Combined platform and step for boat transoms, including a member of angular shape movable to two supported positions in brackets mounted on a boat transom, in one position the angular member providing a narrow step for use in entering the boat, and in the other position the angular member providing an elongate platform from which work may be done upon an outboard motor carried on the boat transom. The apparatus is preferably located adjacent the location of the outboard motor.

ATTORNEY

COMBINED PLATFORM AND STEP FOR BOAT TRANSOMS.

SUMMARY OF THE INVENTION

In the use of boats having outboard motors, it is frequently necessary to perform repairs and cleaning of the motor while the motor is disposed upon the transom of the boat and while the boat is in the water. Frequently work may be necessary while the boat operator is at a location remote from shore and any repair facilities, so that it is incumbent that the work be done at the location of the boat and without undue loss of time. The apparatus may also be used for similar purposes on inboard-outdrive boat units, and may be used for various purposes on substantially any kind of boat, ship, or other apparatus. The apparatus afforded by the invention is designed such that it is out of the way and does not interfere with normal boat operation when it is not being used as a platform, the apparatus in the out of the way storage position still affording a step for use in entering the boat from the water or from a dock or shore.

Other apparatus is not available which will serve the utilities of the subject apparatus. Many steps and ladders are available for use in entering a boat, but none is susceptible to being moved to a position wherein it provides an extended platform from the transom (or other location) of a boat.

Other objects and advantages of the invention will appear from the following detailed description of a preferred embodiment of the invention, reference during the description being made to the accompanying drawings.

BRIEF DESCRIPTIONS OF THE DRAWINGS

FIG. 1 is a side elevation, partly in vertical cross section, showing the stern of a boat having an outboard motor connected to the transom, and showing a preferred embodiment of apparatus according to the invention affixed to the transom.

FIG. 2 is similar to FIG. 1, showing the apparatus of FIG. 1 in an alternate position.

FIG. 3 is a cross sectional view taken at line 3—3 of FIG. 2.

FIG. 4 is an enlarged partial cross sectional view showing a connection assembly of the apparatus.

DESCRIPTION OF THE PREFERRED EMBODIMENT

Referring now to the drawings in detail, and first to FIGS. 1-3, reference numeral 10 indicates a boat, only the rearward stern part of the boat being shown in the drawing figure. An outboard motor 12 is shown connected onto the boat transom 13. A pair of brackets 14,15 are each bolted by a pair of bolts 17,18 to the transom of the boat, the bolts being received through holes through the transom and appropriate washers 19,20 being provided in order that the bolted connections will be waterproof. The upper bolts 17 of each bracket are round-headed and relatively flat, while the lower bolts 18 are large-headed bolts, the heads of the bolts 18 serving as stops as will be later explained.

Each bracket 14,15 is of channel form, the sides having at their edges inwardly projecting ell-shaped flanges 22,23. The bracket channels 14,15 may each be made of a length of a channel form called "Unistrut", or may be otherwise formed as desired or convenient. The flanges 22,23 are retaining flanges.

A step-platform member 30 is of generally ell-shaped form and has a shorter step portion 31 and a longer platform portion 32. Along the opposite sides of each of these there are provided projecting bolt assemblies, each including a bolt 34, nut 35, spacer sleeve 36, and enlarged washer 37 (see FIG. 4). The spacer sleeve 36 may be a short length of pipe. The brackets 14,15 are parallelly spaced apart such that on introduction of a portion of step-platform member 30 to bring either pair of bolt assemblies thereinto from the upper ends of the brackets, the washers 37 will engage within the flange 22 of bracket 14 and within the flange 23 of bracket 15. The washers 37 are sized such that they will be retained behind the flanges 22,23 so that they cannot be moved therefrom except

from the upper ends of the brackets. The large heads of bolts 18 serve as stops to prevent downward movement of the respective sleeve 36 therewith.

The step-platform member 30 is fabricated from a flat channel member, the side flanges being cut at opposite points and the channel member being back-bent at the location to the ell-shape shown in the drawings. A pair of gusset plates 41,42 are bolted in place across the angle of the channel member by two of the bolt assemblies previously described and by additional bolts 43. The angle to which the channel member is bent may be as desired, or as required to match the transom angle of a particular boat. The angle shown in the drawings will be suitable for use with most boat transoms.

The flat channel member from which step-platform member 30 is fabricated may be a channular stair tread. If a stair tread channel is used to fabricate the step-platform member, the tread surface thereof will serve to prevent a person's foot from slipping thereon, since the tread surface is designed for that purpose, having ribs and/or perforations and/or slots in its surface to increase the friction of a person's foot or shoe thereon.

The step-platform member may be disposed in two positions, as shown in FIGS. 1 and 2 of the drawings. In FIG. 1, the shorter portion 31 of the channel is disposed within brackets 14,15, while in FIG. 2 the longer channel portion 32 is placed within the brackets. The step-platform member is simply lifted up out of the brackets and moved to the other position and reinserted to change from the step arrangement of FIG. 1 to the platform arrangement of FIG. 2. With the step-platform member as in FIG. 1, a short step is provided for use in entering the boat, the step also being useful for standing upon if desired for any purpose. In the FIG. 2 position, a longer, more elevated platform is provided alongside the outboard motor so that the motor may be worked on from the platform. Instead of an outboard motor, the boat may be driven by an inboard-outdrive unit, and the platform and step may be used as a work platform as in the case of boats having outboard motor drives.

As will now be apparent, the invention affords a two position device for use on the transoms of outboard or inboard-outdrive boats. In the vertical position of the step-platform member, it can be used to climb into or out of a boat while the boat is on a trailer, or while the boat is in water. While in the vertical position, the apparatus will not interfere with operation of the boat, since it is offset sideways from the motor and is of limited extent beyond the rear of the boat. The apparatus is readily and easily changed from vertical to horizontal position from inside the boat, without use of any tools. The apparatus in the horizontal position can be used for standing upon while working on any part of either an outboard motor or an inboard-outdrive motor unit. The platform is at a level where the lower portion of the drive unit may be readily reached. The jobs for which the platform will be useful include the changing of propellers, replacing of shear pins, untangling of lines, moss, or the like from the propeller, and for many other uses. In using the apparatus, for improvement of safety, it is preferred that portable equipment and passengers within the boat should be moved to forward positions to compensate for the increased load on the rear of the boat, it is preferred that persons working on the platform or step while the boat is in the water use life jackets and/or life lines, it is advantageous to secure the motor on an outboard unit or the lower unit of an inboard-outdrive in the highest position, and it is important to change the step-platform member to the step (vertical) position before commencing operation of the motor after repairs or other work is completed.

While a preferred embodiment of apparatus according to the invention has been described and shown in the drawings, many modifications thereof may be made by persons skilled in the art without departing from the spirit of the invention, and it is intended to protect by Letters Patent all forms of the invention falling within the scope of the following claims.

I claim:

1. Combined step-platform apparatus, comprising an ell-shaped member having a shorter step portion and a longer

platform portion extending from the vertex thereof, at least two spaced projecting elements extending laterally from each side of both said step portion and said platform portion, spaced parallel bracket means adapted to be mounted substantially vertically on an object to which said apparatus is to be connected, said projecting elements at opposite sides of said step portion and at opposite sides of said platform portion being alternatively receivable downwardly to rest in said spaced bracket means and being removable upwardly from said spaced bracket means, whereby said ell-shaped member may be supported by said bracket means in one position with said step portion substantially horizontal and in a second position with said platform portion substantially horizontal.

2. The combination of claim 1, said bracket means each comprising channel means having the channel back mounted against said object and having inwardly projecting flange means from each channel side, said step and platform portions being of channular shape the opposite sides being receivable into said bracket channels, said projecting elements having terminal enlargements adapted to be received in said bracket channels retained behind the inwardly projecting flanges of the outer sides of said bracket channels, and stop means within the lower ends of said bracket channels to prevent

movements of said projecting elements downwardly therewith.

3. The combination of claim 2, each said stop means comprising the head of a bolt disposed through an opening through the back of the respective channel bracket for use in securing the bracket to the object.

4. The combination of claim 2, said ell-shaped member being formed of a channel-formed stair tread having opposite cuts through the sides thereof and back-bent to said ell-shaped form, and having gusset means connected between said step and platform portions to reinforce said step and platform adjacent said vertex.

5. The combination of claim 1, said bracket means being bolted to the transom of a boat whereby said step position of said ell-shaped member provides a step for use in entering the boat and said platform position of said ell-shaped member provides a platform for use in doing work at the stern of the boat.

6. The combination of claim 7, said boat transom being slanted from vertical, the angle of said ell-shaped member being such as to render said step and platform substantially level when said ell-shaped member is supported in said bracket means in the respective step and platform positions.
